FILTRATION UNIT FOR BLOOD AND OTHER MEDICAL LIQUIDS

Frank M. Edwards, West Los Angeles, Calif., assignor to McGaw Division of American Hospital Supply Corporation, Glendale, Calif.

Filed Dec. 31, 1970, Ser. No. 26,714

Term of patent 14 years

Int. Cl. D24—01

U.S. Cl. D16—2

FIG. 1.

FIG. 2.

FIG. 3.

FIG. 4.

FIG. 1 is a top plan view of a filtration unit for blood and other medical liquids embodying my new design;

FIG. 2 is a front elevational view;

FIG. 3 is a bottom plan view; and

FIG. 4 is a cross sectional view taken along line 4—4 of FIG. 1.

I claim:

The ornamental design for a filtration unit for blood and other medical liquids, as shown.
